(57) **CLAIM**

The ornamental design for a pipe clamp, as shown and described.

DESCRIPTION

FIG. 1 is a perspective view of a pipe clamp showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view showing the pipe clamp in a position of use, wherein a screw is screwed into the pipe clamp.
